UNITED STATES PATENT OFFICE.

LEWIS H. KEMPER, OF MILWAUKEE, WISCONSIN.

TEMPORARY BINDER.

SPECIFICATION forming part of Letters Patent No. 392,516, dated November 6, 1888.

Application filed July 16, 1888. Serial No. 280,012. (No model.)

To all whom it may concern:

Be it known that I, LEWIS H. KEMPER, of Milwaukee, in the county of Milwaukee, and in the State of Wisconsin, have invented certain new and useful Improvements in Temporary Binders; and I do hereby declare that the following is a full, clear, and exact description thereof.

My invention relates to temporary binders; and it consists in certain peculiarities of construction and combination of parts, to be hereinafter described with reference to the accompanying drawings, and subsequently claimed.

In the drawings, Figure 1 represents a perspective view of a temporary binder constructed according to my invention; and Fig. 2, a detail view illustrating the means for connecting the binder with a pamphlet or folded sheets of paper. Figs. 3 and 4 are detail views illustrating one of the loops that form part of my invention.

Referring by letter to the drawings, A represents the covers, and B the back, of my temporary binder. Said covers and back, being of the usual material employed in that class of devices to which my invention relates, are flexibly united in the ordinary manner.

Riveted or otherwise suitably secured to the inner side of the back B near the top and bottom thereof are double right-angle plates C, that face each other. The opposing horizontal surfaces of the angle-plates C are cut away to leave a series of pins, e, and secured to the back B midway between said angle-plates is a supporting-block, D; but it is obvious that while I have only shown and described one such block I may employ two or more and arrange them at suitable intervals apart.

The pins e on the angle-plates C are designed to engage the eyes e of loops E, the latter being preferably made of wire so bent that the eye on each loop will be transverse to the length thereof, said wire being turned down at its ends to form prongs f, that pass through the back of the pamphlet, book, or the fold of a series of leaves, F, as best illustrated by the detail, Fig. 4.

In the operation of my invention the prongs f of the wire loops E are passed through the back of the pamphlet, book, or folded leaves F, and then bent down parallel to the length of said loops, the latter being at such dis-

tance apart as to register with the angle-plates C, secured to the back B of the binder. Now by bending the pamphlet, book, or folded leaves in the center the eyes e of loops E can be brought into register with the pins e, forming part of the angle-plates C, and upon the straightening out of said pamphlet, book, or folded leaves said eyes will pass onto said pins and retain the parts in the position best illustrated by Fig. 1. When the pins e and eyes e are in engagement, the block or blocks D support the pamphlet, book, or folded leaves and prevent any sagging toward the back B of the binder. To disconnect a pamphlet, book, or set of folded leaves from the binder, it is only necessary to bend said pamphlet, book, or folded leaves, so as to draw one of the loops off its pin, and, being thus detached at one end, the other loop can be readily separated from its pin by a draw to or from the operator, or by placing the hand under the back of a pamphlet, book, or set of folded leaves and lifting up the same it will bend enough in the center to permit both loops to come off their pins at the same time.

Having thus fully described my invention, what I claim as new, and desire to secure by Letters Patent, is—

1. In a temporary binder, the combination of a series of pins connected to the back of the binder at or near its ends, so as to be clear of said back and have the points of the pins in one series face the points of the pins in the opposite series, the article or articles to be bound, and loops secured to said article or articles and provided with transverse eyes for engagement with said pins, substantially as set forth.

2. In a temporary binder, the combination of a series of pins connected to the back of the binder at or near its ends, so as to be clear of said back and have the points of the pins in one series face the points of the pins in the opposite series, the article or articles to be bound, loops secured to said article or articles and provided with transverse eyes for engagement with the pins, and a supporting block or blocks arranged between said series of pins, substantially as set forth.

3. In a temporary binder, the combination of a double right-angle plate secured to the back of the binder at or near each end thereof,

and the opposing horizontal surfaces of each plate cut away to leave a series of pins, the article or articles to be bound, and loops secured to said article or articles and provided with transverse eyes for engagement with the pins, substantially as set forth.

4. A temporary binder consisting of the covers A, back B, plates C, cut away to leave the pins e, the article or articles to be bound, to and the wire loops E, provided with the trans-

verse eyes e and prongs f, substantially as set forth.

In testimony that I claim the foregoing I have hereunto set my hand, at Milwaukee, in the county of Milwaukee and State of Wisconsin, 15 in the presence of two witnesses.

LEWIS H. KEMPER.
